UNITED STATES PATENT OFFICE

2,678,156

ROTARY AIR COMPRESSOR

Stanford A. Henderson, Buffalo, N. Y., assignor to Gomco Surgical Manufacturing Corp., Buffalo, N. Y., a corporation of New York

Application December 14, 1950, Serial No. 200,765

4 Claims. (Cl. 230—152)

1

This invention relates to improvements in rotary air compressors and more particularly to such an air compressor for use in dental offices.

In most dental offices there are tools and instruments which operate on compressed air. These tools and instruments are sometimes used intermittently and it is essential that a supply of compressed air at the desired operating pressure, which is usually from 20 to 40 pounds per square inch, be available at all times. At the present time the supply of compressed air is usually provided by a rather large unit which includes an electric motor, a compressor driven thereby and a storage tank. The storage tank is required to maintain a suitable volume of compressed air at the desired pressure so that it will be immediately available for operating the tools or instruments when use thereof is commenced. The bulk of the presently used unit is so great that a considerable amount of office floor space is taken up and because of this the unit is sometimes placed outside the office and air lines are run into the interior of the office from the remotely located storage tank.

An important object of the present invention is to provide a compressor unit of the type described which is compact and occupies a small amount of floor space and can be readily mounted on a shelf or in a cabinet or closet or any other desired place.

Another important object is to provide a rotary compressor which develops a relatively high pressure in a matter of seconds.

Another object is to provide such a compressor which develops such an immediate pressure that the need for storage tanks for most installations is eliminated.

Another object is to provide such a compressor unit in which condensation of moisture from the compressed air is reduced to a minimum.

A further object is to provide such a compressor which is self-lubricating, requires little maintenance, is not likely to get out of order or require repair and is relatively inexpensive to manufacture.

Other objects and advantages of the invention will be apparent from the following description and accompanying drawings in which:

Fig. 1 is a diminutive perspective view of a compressor unit embodying my invention.

Fig. 2 is an enlarged vertical transverse sectional view of the compressor shown in Fig. 1, the view being taken on line 2—2, Fig. 3.

Fig. 3 is a side view of the motor and compressor unit shown in Fig. 1, the motor being

2 shown in elevation and the compressor being shown in vertical central longitudinal section.

Fig. 4 is a vertical transverse sectional view of the compressor and taken on line 4—4, Fig. 3.

Fig. 5 is another vertical transverse sectional view thereof but showing the rotor in a different position, the view being taken on line 5—5, Fig. 3.

Fig. 6 is an enlarged fragmentary sectional view of one of the baffles in the stator of the compressor and taken on line 6—6, Fig. 4.

Fig. 7 is a vertical transverse sectional view of the compressor and taken on line 7—7, Fig. 3.

Fig. 8 is an enlarged side elevational view of the filter trap shown in Fig. 1.

Fig. 9 is a vertical central longitudinal sectional view thereof and taken on line 9—9, Fig. 8.

Fig. 10 is a horizontal transverse sectional view thereof and taken on 10—10, Fig. 9.

Fig. 11 is an enlarged fragmentary sectional view through the air intake of the compressor and taken on line 11—11, Fig. 1.

Fig. 12 is an enlarged fragmentary sectional view through the compressed air outlet of the compressor and taken on line 12—12, Fig. 1.

Fig. 13 is a fragmentary plan view of the ports in the stator of the compressor and taken on line 13—13, Fig. 5.

Fig. 14 is a developed circumferential sectional view of the stator and taken on line 14—14, Fig. 5.

In accordance with the invention the compressor unit is shown as comprising generally an electric motor 15, a rotary air compressor 16 and a filter trap 17. The motor 15 may be of any suitable type and the compressor 16 is preferably arranged to form one end bell for the motor as shown, thus providing a compact unit which is resiliently mounted on the upturned arms of a U-shaped support 18 carried by a base plate 19.

The rotary compressor 16 comprises a stator including inner and outer cylindrical casings 20 and 21 respectively connected by an integral inner end head 22, and a removable outer end head 23.

A series of screws 27 are shown as securing the removable outer end head 23 to the casing walls 20 and 21. On the side of the inner end head 22 opposite from the outer casing 21, the stator is formed with an axially extending cylindrical integral flange 24 which abuts against the housing of the motor 15.

To mount the stator on the motor the flange 24 is interiorly formed with a series of circumferentially spaced bosses 25 which are provided with threaded holes to receive longitudinal tie bolts 26 connected with the motor housing, as shown in Fig. 3.

The armature shaft 23 of the motor 15 is shown

as extending through the inner end wall 22 and into the compression chamber 29 surrounded by the inner cylindrical casing 20. The shaft 28 is shown as journaled in a sleeve bearing 30 carried by the inner end wall 22 and this bearing may be lubricated by an oil soaked bat of absorbent material 31 or in any other desired manner. Oil can be applied to the bat 31 through a vertical tube 32 leading to the exterior of the flange 24, as shown in Fig. 3.

The compression chamber 29 is cylindrical but has its axis arranged eccentrically with respect to the axis of the shaft 28 as shown in Figs. 2, 4, 5 and 7. A cylindrical rotor 33 is arranged within the chamber 29 so that its periphery is eccentric to the bore of this chamber and is non-rotatably mounted on the shaft 28. The rotor 33 is provided with a series of circumferentially spaced slots 34 which extend longitudinally the full length of the rotor and open to the periphery thereof but have their inner longitudinal ends terminating short of the shaft 28. Three such slots 34 are shown although any number desired may be employed. A blade or vane 35 is slidably arranged in each slot 34 for radial movement, the outer longitudinal end faces of these vanes engaging the cylindrical wall of the compression chamber 29 and the inner longitudinal end faces at all times being spaced from the bottoms of the slots for a purpose hereinafter described. The radial end faces of the vanes 35 closely fit the opposing inner end faces of the end walls 22 and 23. The shaft 28 drives the rotor 33 to rotate in a clockwise direction as viewed in Figs. 2, 4 and 5.

Air is supplied to the working spaces between adjacent pairs of vanes 35 to be compressed as the rotor 33 rotates. For this purpose, the inner and outer cylindrical casings 20 and 21 respectively of the stator are spaced apart to provide an annular space which is divided off by partitions 38 and 39 to provide an air inlet chamber 40 and a compressed air outlet chamber 41. The partitions 38 and 39 are circumferentially spaced one from the other with the lower partition 38 arranged at about a seven o'clock position and the upper partition 39 at about a 12 o'clock position as viewed in Figs. 2, 4 and 5. The partitions 38 and 39 are preferably formed integrally with the inner and outer casings 20 and 21 respectively as shown.

A series of circumferentially spaced radial baffles 42 are arranged in the air inlet chamber 40, two such baffles being shown with one arranged adjacent the partition 38 and the other adjacent the partition 39. As best shown in Fig. 14, the baffle 42 adjacent the partition 39 extends flush from the outer end faces of the casings 20 and 21 longitudinally to a point short of the inner end wall 22 so as to leave a passage connecting the chambers on opposite sides of this baffle. Similarly but in a reversed arrangement, the other baffle 42 adjacent the partition 38 projects axially outwardly from the inner end wall 22 and terminates short of the end faces of the casings 20 and 21 so as to leave a connecting passage between the chambers on opposite sides of this baffle.

Air is admitted from the atmosphere into the air inlet chamber 40 through an inlet opening 43. This opening 43 is arranged in the removable cover or end wall 23 and communicates with that portion of the chamber 40 arranged between the upper partition 39 and the adjacent baffle 42 as shown in Fig. 14. The air entering the inlet open-

ing 43 is preferably first filtered through a filter device 44 connected to the end wall 23 as shown in Fig. 11. The filter device may be of any suitable construction. The chamber 40 is preferably packed with a fibrous material such as wool fibers 45 as shown in Fig. 2 so that the air passing back and forth past the baffles 42 is filtered a second time.

A port 46 is shown in Fig. 5 as extending radially through the inner casing 20 and connects the air inlet chamber 40 with the compression chamber 29. The port 46 is arranged adjacent the lower partition 38 and between the same and the adjacent baffle 42. The inner end of the port 46 is enlarged and extends circumferentially principally in a counterclockwise direction from the port as shown at 46 in Figs. 5 and 13.

An exhaust port 49 is arranged in the inner casing adjacent the intake port 46 and has its inner end also enlarged in a circumferential direction as indicated at 50 in Figs. 5 and 13. The circumferential enlargement 50 extends in a clockwise direction from the exhaust port 49 as viewed in Fig. 5. Thus as the rotor 33 rotates in a clockwise direction as viewed in Fig. 5, air passes through the intake port 46 into the compression chamber 40 and pockets or bodies of air are trapped between adjacent pairs of blades 35 and compressed during continued rotation of the rotor and the compressed air is exhausted through the port 49 into the compressed air outlet chamber 41.

The upper part of the arcuate compressed air outlet chamber 41 is traversed by a series of alternately staggered circumferentially spaced baffles 51, four such baffles being shown. The uppermost baffle 51 begins flush with the coplanar outer faces of the inner and outer casings 20 and 21 respectively and extends axially of the stator terminating short of the opposing face of the inner end wall 22. The next succeeding baffle 51 is reversely arranged so that it extends axially from the inner end wall 22 and terminates short of the outer end wall 23. In similar manner the succeeding baffles 51 are alternately arranged. The upper faces of these baffles 51 are slanted downwardly toward their free radial ends for drainage purposes as best shown in Fig. 6.

An outlet 52 for the compressed air in the chamber 41 is provided in the removable cover or end wall 23 and is arranged so as to communicate with this chamber between the partition 39 and the first adjacent baffle 51. A tubular conduit or pipe 53 is suitably connected at opposite ends to the outlet 52 and the inlet 54 of the filter trap 17.

It will be seen that the air inlet and outlet chambers 40 and 41 respectively are in the form of arcuate chambers of substantial extent which surround the compression chamber 29. Also, the air inlet 43 and compressed air outlet 52 are conveniently arranged adjacent each other at the top of the stator. Further, the inlet 43 is at the trailing end of and the intake port 46 at the leading end of the arcuate air inlet chamber 40 while the outlet 52 is at the leading end of and the exhaust port 49 is at the trailing end of the arcuate compressed air outlet chamber 41, relating the location of these openings to the unidirection of rotation of the rotor 33. The air is compelled to follow circuitous paths between respective sets of openings.

An important feature of the rotary compressor 16 is that the fluid pressure on the inner and outer longitudinal end faces of the blades or vanes

35 tends to be equalized at all times during operation of the compressor so that centrifugal force can act on these blades or vanes to urge the same outwardly against the surrounding wall of the compression chamber 29 and thereby insure a good seal between this wall and these blades or vanes. As previously described, the blades 35 never bottom in the slots 34 even when the vanes are in their most retracted position as shown by the lowermost blade in Fig. 5. This leaves a longitudinally extending chamber or space under each blade and the corresponding outer ends of these chambers communicate with a circular recess 55 in the outer end face of the rotor 33 as shown in Fig. 2.

Referring to Fig. 3, the annular recess 55 communicates with the inner end of a horizontal passage 56 which at its outer end communicates with a vertical passage 58. The passages 56 and 58 are formed in the removable cover or outer end wall 23 which is enlarged centrally to provide an outwardly projecting tubular neck 59 which surrounds a chamber 60. This chamber 60 is formed as an axial recess in the tubular neck 59 and has its inner end closed. The outer end of the chamber 60 is closed by a glass cover 61 held against the outer end face of the tubular neck 59 by a removable ring 62.

The upper end of the vertical passage 58 communicates with the chamber 60 and its lower end communicates with a filling hole 63. The filling hole 63 extends axially of the stator through the removable cover or outer end wall 23 so that the inner end of this hole communicates with the lower part of the compressed air outlet chamber 41. The outer portion of this filling hole 63 is surrounded by a tubular neck 64 formed integrally with the end wall 23 and extending outwardly therefrom. The outer end of this tubular neck 64 is shown as arranged in an enlarged hole 65 in the adjacent upturned arm of the U-shaped support 18. A T fitting 66 is mounted on the outer end of the tubular neck 64 and has its lateral branch extending upwardly and closed by a removable plug 68. A screw plug 69 closes the outer end of the T fitting 66. The interior passages of the T fitting 66 communicate with the filling hole 63.

Thus it will be seen that if either plug 68 or 69 is removed, hydraulic fluid such as oil can be forced into the compressed air outlet chamber 41, the passages 63, 58, and 56, the chamber 60, the annular groove 55 and the spaces at the bases of the slots 34 unoccupied by the blades 35. Sufficient oil is inserted so that a body 70 is provided in the bottom of the compressed air outlet chamber 41 and the passages 63, 58, 56, groove 55 and the chambers at the bases of the slots are completely filled, while the chamber 60 need not be completely filled.

Referring to Fig. 5 it will be seen that the compressed air discharged from the exhaust port 49 is in direct contact with the body of oil 70 and thereby transmits its pressure to it. This pressure is transmitted through the stationary passages 63, 58 and 56 to the annular groove 55 on the rotor which in turn transmits the pressure to the slots 34 and the inner longitudinal ends of the blades 35. Since the bases of the slots 34 are interconnected through the annular groove 55, oil can be displaced from any slot and fed to any other slot as will occur when the blades 35 move radially in and out of their slots during rotation of the rotor. The horizontal passage 56 is

of relatively small diameter so that interflow between the slots 34 is promoted.

The body of oil 70 may become agitated by the compressed air discharged by the exhaust port 49 and thus cause this oil to foam up. If oil with entrained air bubbles works into the vertical passage 58 the air bubbles will rise into the chamber 60 passing the entrance to the horizontal restricted passage 56. In this way the oil admitted to the rotor is purged of air. Also, a sufficient body of oil is maintained in the chamber 60 to serve as a reservoir to insure a constant supply of oil to the slots 34.

Inasmuch as the blades 35 have a sliding fit in the slots 34, some of the pressurized oil at the inner ends of these blades will work out radially and longitudinally of the slots and serve to lubricate the sliding surfaces.

It will be seen that the entrapped air between adjacent pairs of blades 35 will tend to leak past the sliding joint between the outer longitudinal end faces of the blades and the wall of the compression chamber 29 which they engage. However, such leakage is defeated by reason of the pressurized oil pressing against the inner longitudinal end faces of the blades 35 and urging these blades into a firm contact with the wall. The pressure of the oil will be always at least equal to the pressure of the air so trying to leak past the vanes 35. Moreover, centrifugal force working on the vanes 35 urges them outwardly into still firmer engagement with the compression chamber wall so that there is always a preponderant force urging the vanes outwardly regardless of the pressure of the compressed air and oil.

Leakage of compressed air past the vanes has been a defect of rotary compressors as heretofore constructed and it will be seen that my rotary compressor effectively overcomes this undesirable condition and also makes possible a compressor of smaller size for a given pressure rating.

It will also be seen that any entrained oil in the compressed air discharged by the exhaust port 49 will be separated from the air by reason of the fact that the compressed air is caused to follow a circuitous path back and forth past the baffles 51 as it moves toward the outlet 52. The successive and sudden reversals of air flow will tend to separate the compressed air and entrained oil. The so separated oil collects along the upper slanted sides of the baffles 51 and drains off the radial free edge thereof onto the next lower baffle and so on until the separated oil rejoins the main body of oil 70 in the bottom of the stator.

While the compressor and motor unit may be mounted on the U-shaped support 18 in any suitable manner, it is shown as resiliently mounted at opposite ends by a rubber ring 71 clamped by a strap device 72 to the corresponding upturned arm of the support 18, as shown in Figs. 1 and 3.

Referring to Figs. 8-10, the filter trap 17 is shown as comprising a cylindrical tubular body 75, an upper end head 76 and a lower end head 77. The opposite ends of the tubular body 75 seat against gaskets 78 arranged in annular recesses provided in the end heads 76 and 77. The end heads 76 and 77 are held firmly on the tubular body 75 by a tie bolt 79 arranged centrally within the tubular body and which extends longitudinally thereof, the upper threaded end of the tie bolt being screwed into a threaded recess

in the upper end head 76 and the lower end extending through a central opening in the lower end head 77 and being threaded to receive a nut 80 arranged below the end head 77 and bearing thereagainst.

The upper end head is shown as provided with the horizontal inlet 54 and a horizontal outlet 81 on opposite lateral sides, a front horizontal passage which communicates with a pressure gauge 82 and a vertical passage which communicates with a pressure switch 83. The gauge 82 and switch 83 are suitably mounted on the upper end head 76. The pressure switch 83 may be of any suitable type and is electrically connected with the electric motor 15 through the line 84 and has for its function to energize and de-energize the motor in accordance with a predetermined setting of the switch for a particular desired pressure of compressed air within the filter trap 17. Thus when the pressure within the filter trap drops below the predetermined setting the pressure switch 83 operates to energize the motor 15 by connecting the line 84 with a current supply line 85. On the other hand when the pressure within the filter trap exceeds the said predetermined setting the pressure switch 83 operates to interrupt current flow to the motor 15.

The hollow interior of the filter trap is divided into a relatively small upper chamber 86 and a larger lower chamber 88 by a filter disk 89. This filter disk 89 may be made of any suitable material such as fiberglass and has its periphery closely fitting the wall of the tubular body 75 and is held on the tie rod 79 which extends through it in any suitable manner as by the clip 90. This clip 90 is shown as having legs biased toward each other and arranged on opposite sides of the tie rod 79 so as to clamp the clip on this rod, the filter disk 89 resting on the clip and being supported thereby.

Compressed air entering the filter trap 17 through the inlet 54 is led to the lower chamber 88 by the tube 91. This tube 91 open at both ends is shown as extending vertically through a closely fitting hole in the filter disk 89 being screwed into a threaded hole in the upper end head 76 which communicates with the inlet 54.

The compressed air so discharged into the lower chamber 88 is likely to contain volatile matter which condenses in this chamber, collecting in the bottom thereof. The compressed air escapes through the disk filter 89 to the upper chamber 86 and enters the outlet 81 to which a line 92 can be connected. This line 92 leads to the desired tool, instrument or equipment to be operated on compressed air. Condensate can be withdrawn from the lower chamber 88 from time to time by a drain cock 93 shown as mounted on the lower end head 77.

A fitting 94 is shown in Fig. 9 as mounted on the upper end head 76 to connect the conduit 53 with the inlet 54. A check valve 95 is preferably arranged in the fitting 94 and the same is shown as a disk seating against a shoulder 96 facing the inlet and urged thereagainst by a coil spring 98. Thus the check valve 95 prevents back flow of compressed air from the filter trap 17 to the compressor 16 when the rotor 15 is not running. However, this valve disk 95 is lifted off its seat 96 against the urging of the spring 98 when the compressor is delivering compressed air to the filter trap.

Primarily the purpose of the filter trap 17 is to condense the volatile components in the com-

pressed air and secondarily to provide a small storage space for the compressed air. However, the volume of compressed air held in the filter trap is very small compared with the relatively much larger storage tanks employed with conventional compressor units presently used.

The upper end head 76 is shown as provided at its rear with an upstanding flange 99 having holes to receive screws 100 whereby the filter trap can be conveniently mounted on any suitable support.

It will be noted that the double casing walls 26 and 28 connected by the partitions 38 and 39 and the baffles 42 and 51 provide an extensive surface for radiation of heat developed from compressing the air in the compressor. This effective way of dissipating the heat developed reduces the temperature of the compressed air delivered to the filter trap 17 and hence minimizes the amount of condensate collecting within the filter trap.

From the foregoing it will be seen that the present invention provides a compact and efficient compressor unit which requires only very infrequent attention and which produces immediately available compressed air at relatively high pressure.

While the invention has been described with particular reference to apparatus for a dental office, it will be understood that this is illustrative and not limitative of the invention.

I claim:

1. A rotary compressor, comprising a stator having inner and outer spaced annular casing walls, a compression chamber surrounded by said inner casing wall, partitions connecting said inner and outer casing walls and spaced one from the other to provide air inlet and outlet chambers each of substantial circumferential extent, rotary means arranged within said compression chamber for compressing air therein, means providing an intake port connecting said inlet and compression chambers only at the leading end of said inlet chamber, means providing an air inlet to said inlet chamber only at the trailing end thereof, means providing an exhaust port connecting said outlet and compression chambers only at the trailing end of said outlet chamber, means providing a compressed air outlet from said outlet chamber only at the leading end thereof, and baffles arranged in said inlet and outlet chambers and extending generally longitudinally of said stator and connecting said inner and outer casing walls and alternately staggered to provide a circuitous path for the air flowing from said inlet to said intake port and also a circuitous path for the compressed air flowing from said exhaust port to said outlet.

2. A rotary compressor, comprising a stator having inner and outer spaced annular casing walls, a compression chamber surrounded by said inner casing wall, partitions connecting said inner and outer casing walls and spaced one from the other to provide air inlet and outlet chambers each of substantial circumferential extent, rotary means arranged within said compression chamber for compressing air therein, means providing an intake port connecting said inlet and compression chambers only at the leading end of said inlet chamber, means providing an air inlet to said inlet chamber only at the trailing end thereof, means providing an exhaust port connecting said outlet and compression chambers only at the trailing end of said outlet chamber, means providing a compressed air outlet from said outlet

chamber only at the leading end thereof, a filter device filtering air entering said inlet chamber through said inlet, and fibrous material arranged in said inlet chamber to filter air flowing therethrough from said inlet toward said intake port.

3. A rotary compressor, comprising a stator having inner and outer spaced annular casing walls arranged with their axes generally horizontal, a compression chamber surrounded by said inner casing wall, rotary means arranged within said compression chamber for compressing air therein and including a slotted rotor and blades movably arranged in such slots, partitions connecting said inner and outer casing walls adjacent the top and bottom thereof to provide separate air inlet and outlet chambers of substantial circumferential extent, a body of oil contained within the bottom of said outlet chamber, passage means connecting said oil body with the inner ends of said rotor slots in all rotative positions of said rotor, said inner casing wall being provided with an exhaust port above the level of said oil body and connecting said outlet and compression chambers and serving to impose the pressure of the compressed air discharged through said exhaust port on said oil body so as to fill said passage means and said inner ends of said slots with such oil, means providing a compressed air outlet from said outlet chamber at the upper end thereof and remote from said exhaust port, baffles arranged in said outlet chamber at circumferentially spaced intervals and extending generally longitudinally of said stator and connecting said casing walls and alternately

staggered to provide a circuitous path for the compressed air flowing from said exhaust port to said outlet whereby oil entrained in said compressed air is urged to separate therefrom and allowed to drain down to said oil body, said inner casing wall being provided with an intake port connecting said inlet and compression chambers, and means providing an air inlet to said inlet chamber circumferentially remote from said intake port.

4. A rotary compressor as defined in claim 3 in which said baffles extend radially between said inner and outer casing walls and have their upper surfaces sloping downwardly in a direction longitudinally of said stator toward their free edge to facilitate the draining of oil.
